KNITTING MACHINE AND PROCESS FOR
KNITTING BÉRET CAPS AND THE LIKE

Louis Borsook, Toronto, Ontario, Canada

Application December 1, 1933, Serial No. 700,518

7 Claims. (Cl. 66—48)

The invention relates to improvements in a machine for knitting bérét caps in which the process is achieved by reciprocatory knitting of a plurality of integral segments.

5 The method heretofore in use, described in U. S. patent to Charles W. Stout, No. 1,843,101, on January 26, 1932, employs the usual Scott & Williams type of revolving needle cylinder seamless hosiery machine and bérêts manufactured under 10 same and under U. S. patent to Charles W. Stout on 26th January, 1932, No. 1,843,100, possess certain undesirable features. Chiefly these are:— Firstly—insufficient fashioning results in a bérét cap requiring a relatively large amount of 15 blocking, and even then unable to retain its proper shape under ordinary conditions of wear, and secondly—the lack of a substantial hat-band or turn-back knitted integrally with each segment. This invention particularly seeks to cure these 20 deficiencies and incidentally other improvements are introduced hereinafter described.

Referring to the drawings:

Fig. 1 is a plan view of the needle circle showing the various cams and the down picker.

25 Fig. 2 is an elevation of the machine partly broken away, embodying the invention.

Fig. 3 is an elevation of the hat band cam and its connecting parts indicating the general construction and manner of mounting same, viewed 30 from the front of the machine.

Fig. 4 is an elevation from a different view of a detail shown in Fig. 3.

Fig. 5 is a development of the needle cylinder showing the relation of the needles to the various 35 cams at the end of the first course and before any needles have been picked down.

Fig. 6 is similar development to Fig. 5 at the end of the last course immediately before the hat-band needles are thrown into action.

40 Fig. 7 is the same as Fig. 6 after the hat-band needles have been picked down.

Fig. 8 is an elevation viewed from the centre of the machine of the down picker and switch cam.

45 Fig. 9 is a vertical sectional view through the down picker at the instant of engagement.

Fig. 10 is similar to Fig. 9 at the instant prior to disengagement.

50 Fig. 11 is an enlarged plan view of the down picker.

Fig. 12 is an elevation of the detail in Fig. 11.

Fig. 13 is a schematic representation of successive gores or segments of a bérét indicating the arrangement of needles.

55 Fig. 14 is a plan view of a bérét cap, bottom

up, showing the increased fashioning and the hat-band or foldover.

Fig. 15 is top view of the bérét in Fig. 14.

The improved machine herein described, like the one described in the aforesaid U. S. Patent No. 1,843,101, knits segments or gores in integral succession, and the machine shown in the drawings is of the general type described in U. S. patent to Robert W. Scott on September 7, 1915, No. 1,152,850. The invention herein described employs 10 a novel arrangement of needles shown in Figures 1, 5, 6, 7 and 13. The crown needles "C" are provided with medium butts; the ever-active needles (that is the needles which knit the periphery of the shaped bérét) "E" have short butts; the 15 needles on the head side "H" have medium butts; and the hat-band needles "B" have long butts. In addition to these groups there are two groups of two needles each, in the hat band division 1 and 2, which last mentioned needles have long butts 20 and normal shanks but the heads are removed; these needles produce a blank stitch to facilitate the foldover in the hat-band.

Previously also machines of this type in most common use employed two down pickers or widen- 25

ing pickers, each adapted to throw two needles into knitting relation; in this invention one down picker is constructed with the capacity to throw four or five needles into knitting relation. This modification is necessary to afford an extension of 30

the number of needles employable in the crown group where the size of the needle cylinder is fixed, accordingly it is now possible to adapt the standard machine to permit the addition of thirty 35 to forty needles in this group. The space occupied by these additional needles was previously

of necessity filled with short butt or ever-active needles and corresponds roughly to the distance separating the two downpickers on the aforesaid 40 previously employed machine, these must be spaced sufficiently apart to avoid interference of one with the other. These additional needles now

provide the hat-band without detracting from the size of the bérét. It will also be seen that by 45 picking down a greater number of needles on each reciprocation it becomes possible to commence with a lesser number of ever active needles and still retaining the same number of courses the segment or gore will possess a definitely longer

taper, thereby yielding a better fashioned product. In practice it has been found that bérêts made by this improved method require relatively 50 very little blocking to produce the required shape and may not thereafter be readily distorted out

55

of shape by exposure to weather or by rough handling.

The knitting of the hat-band which is claimed as part of this invention is accomplished by throwing all needles "B" into knitting relation as a group at a predetermined point in each gore; this is achieved by cam 4 acting upon these needles each of which has a long butt. The mechanism for this purpose is shown in Figures 2 and 3 in which 7 represents the bed plate provided with a stationary upright arm 5 drilled to receive and allow horizontal movement of the shank 6 of a cam member 4; a suitable adjusting screw 8 in the end of the shank opposite to the cam is designed to co-act with a tiltable cam 9, which cam comprises a rounded portion in contact with the adjusting screw and eccentrically pivoted at 10 in a stationary upright arm 15 on the bed plate; a pivot 11 at the opposing end of cam 9 is engaged in a slot formed by spacing two adjustable fingers 12 and 13 by means of set screws on an upwardly extending member 14 capable of vertical movement and thereby activating cam 9. The said upwardly extending member 14 is adapted to have motion transmitted to it through a rod 14' attached to an arm 24 swingably mounted on the chassis of the machine at 27, the said rod being provided at one end with a member 22 having a slot carrying bolted therein an adjustable contact finger 16 designed to co-operate with lugs 17 on an endless moving chain 19. The manner of bolting the contact finger into the aforesaid slot may be achieved in any orthodox manner and is not indicated in the drawings. An upwardly extending member 18 piercing the bed plate is intended to guide vertical movement. Lugs 17 in addition to operating hat band cam 4 also operate switch cam 28 through connecting rod 21. It will be seen that by adjusting contact finger 16 in slot 22 the hat band cam 4 may within limits be activated at any desirable point in each gore. A spiral spring 23 is provided to bring the hat band cam out of engagement and a similar spring 28 is provided to insure proper contact between finger 16 and chain 19.

The movement imparted to rod 14' through the lugs 17 is eventually transmitted in the form of vertical displacement by means of trough 25 positioned at the remote end of the rod designed to co-operate with a wheel 26 affixed in the lower terminus of the guide rod 18, these take up all horizontal movement and only vertical displacement is transmitted through the upwardly extending member.

In the improved process the knitting preferably commences at the shortest course; this in practice has been found to be more satisfactory than commencing at the longest course and picking needles up described in the before mentioned patents to Charles W. Stout. This first course by my method may be knitted with as few as ten needles, since the downpicker functions only with the needles adjoining the ever active needles E. The minimum number of such needles for the first course is determined by the spread of the downpicker. In the illustration E represents twelve needles; the first course is therefore made on twelve needles, assuming same to have commenced on the clockwise reciprocation a second course is knitted on the counter clockwise reciprocation on the same needles, but before the return reciprocation has been completed four needles on the crown side are picked down and the third course is knitted on sixteen needles, on the

return another course is knitted on the same needles. Since the last needle in any one course forms the first needle on the return course, in the knitting process this needle is again picked up, thus four needles are picked down and one is picked up. Before the return reciprocation is completed four needles are now picked on the head-side and again two courses knitted and so on until 16 double courses have been knitted when the hat-band cam 4 is thrown into action, thereby lowering all the long butt needles B. (In the illustration these amount to 20 including the two groups of blank needles.) All needles are now down on the head side and the downpicker continues to co-act with the crown needles only until the largest course has been knit when, as formerly, the switch cam is brought into action to raise all but the ever active or short butt needles E out of activity and the process is repeated until the bérêt is complete. The needles in the hat band designed to yield blank stitches are shown in Fig. 13 by dotted lines 1' and 2', these facilitate folding and conversely re-act against unfolding of the hat-band. Previous to my invention bérêts were knitted using only three groups of needles, i. e. crown, ever active and head-side numbering respectively 34, 37 and 18; within certain limits the relationship of the needles could be varied but since the number of ever active needles must remain in the vicinity of 37 or therabouts, no attempt at proper fashioning is possible. In my process the three groups may be 81 for the crown, 10 for the ever active needles and 45 for the head-side in addition to from 20 to 40 needles for the hat-band, depending on how wide a band is desired. It will be apparent by inspecting Figures 14 and 15 that by virtue of reducing the number of ever active needles the fashioning of each gore may be brought very nearly to the maximum diameter of the bérêt.

I claim:

1. In combination with a circular reciprocatory knitting machine adapted to knit integrally a plurality of shaped segments to form a bérêt cap, a needle cylinder having a series independent needles arranged in adjacent groups of varying butt lengths; a widening picker with a needle engaging wing on each side of its operative end designed to co-act with a plurality of needles composing certain groups and bring same into knitting relation at opposing ends of the series of needles in active position at each oscillation until such needles are exhausted; cam means for lowering into action all needles of a certain other group as a unit at a predetermined point intermediate in said segment to knit an integral hat-band or fold over; cam means for raising all but ever-active needles out of action at the completion of each segment.

2. In combination with a circular reciprocatory knitting machine adapted to knit integrally a plurality of shaped segments to form a bérêt cap, a needle cylinder having a series of independent needles arranged in adjacent groups of varying butt lengths wherein the group at one end of the said series comprises medium butt crown needles adjacent to a second group of short butt ever-active needles which in turn is adjacent to a third group of medium butt head-side needles and lastly a group of long butt hat-band needles, such last group embracing two aggregations of long butt needles with part of the operative heads removed to form blank stitches disposed respectively midway therein and at the point of junc-

- tion of the said two last mentioned groups of needles; a widening picker with a needle engaging wing on each side of its operative end designed to co-act with a plurality of medium butt 5 needles and bring same into knitting relation at opposing ends of the series of needles in active position at each oscillation until such needles are exhausted; cam means for lowering into action all long butt needles as a unit at a predetermined point intermediate in said segment to knit an integral hat-band or fold over; cam means for raising all but ever-active needles out of action at the completion of each segment.
3. In combination with a circular reciprocatory knitting machine adapted to knit integrally a plurality of shaped segments to form a bérét cap, a needle cylinder having a series of independent needles arranged in adjacent groups of varying butt lengths, wherein the group at one 10 end of the said series comprises medium butt crown needles adjacent to a second group of short butt ever-active needles which in turn is adjacent to a third group of medium butt head-side needles and lastly a group of long butt hat-band needles, such last group embracing two aggregations of long butt needles with part of the operative heads removed to form blank stitches disposed respectively midway therein and at the point of junction of the said two last 15 mentioned group of needles; a widening picker with a needle engaging wing on each side of its operative end designed to co-act with four medium butt needles and bring same into knitting relation at opposing ends of the series of needles in active position at each oscillation until such needles are exhausted; cam means for lowering into action all long butt needles as a unit at a predetermined point intermediate in said segment to knit an integral hat-band or fold over; such means comprising a shank 20 mounted cam member adapted to horizontal movement in and out of needle engagement, an adjustable screw in the free end of said cam shank engaging the rounded edge of a tiltable cam eccentrically pivoted relative to such edge and mounted in a manner to impart horizontal movement thereto upon activation, a device to control movement of said last mentioned cam consisting of a vertically movable rod carrying an adjustable horizontally extending member at its upper terminus slotted to engage a pin extending from 25 the free end of said tiltable cam and having at its lower terminus a wheel acting in a grooved member supported on a side extension of the free end of an arm mounted in a swingable manner to impart vertical movement to said rod and held in 30 operative relation to suitably spaced lugs in a moving chain through an adjustable contact finger disposed on a similar side extension in the opposing direction of said arm; spring means for returning said first mentioned cam to a position 35 of disengagement; cam means for raising all but ever-active needles out of action at the completion of each segment.
4. In combination with a circular reciprocatory knitting machine adapted to knit integrally a plurality of shaped segments to form a bérét cap, a needle cylinder having a series of independent needles arranged in adjacent groups of varying butt lengths, wherein the group at one end of the said series comprises medium butt crown needles adjacent to a second group of short butt ever-active needles which in turn is adjacent to a third group of medium butt head-side needles and lastly a group of long butt hat-band needles, such last group embracing two aggregations of long butt needles with part of the operative heads removed to form blank stitches disposed respectively midway therein and at the point of junction of the said two last mentioned groups of needles; a widening picker with a needle engaging wing on each side of its operative end 40 designed to co-act with four medium butt needles and bring same into knitting relation at opposing ends of the series of needles in active position at each oscillation until such needles are exhausted; cam means for lowering into action all long butt needles as a unit at a predetermined point intermediate in said segment to knit an integral hat-band or fold over; such means comprising a shank mounted cam member adapted to horizontal movement in and out of needle engagement, an adjustable screw in the free end of said cam shank engaging the rounded edge of a tiltable cam eccentrically pivoted relative to such edge and mounted in a manner to impart horizontal movement thereto upon activation, a device to control movement of said last mentioned cam consisting of a vertically movable rod carrying an adjustable horizontally extending member at its upper terminus slotted to engage a pin extending from 45 the free end of said tiltable cam and having at its lower terminus a wheel acting in a grooved member supported on a side extension of the free end of an arm mounted in a swingable manner to impart vertical movement to said rod and held in 50 operative relation to suitably spaced lugs in a moving chain through an adjustable contact finger disposed on a similar side extension in the opposing direction of said arm; spring means for returning said first mentioned cam to a position 55 of disengagement; cam means for raising all but ever-active needles out of action at the completion of each segment.
6. In the process for making bérét caps on a circular reciprocating machine adapted to knit integrally a plurality of shaped segments, the steps of reciprocating a group of ever-active needles with groups of needles in idle position, of the symmetrical lowering of a plurality of needles into action at opposing ends of the series of needles in active position at each oscillation by means of a widening picker until a predetermined point in each gore is reached and thereafter lowering all needles on the head side of the said segment 60 by means of a cam and continuing the widening with the said picker at the crown end only.
7. In the process for making bérét caps on a circular reciprocating machine adapted to knit integrally a plurality of shaped segments the steps 75

of reciprocating a group of ever-active needles with groups of needles in idle position of symmetrically lowering four needles into action and lifting one needle out of action at opposite ends of the series of needles in active position at each oscillation by means of a widening picker and continuing thus to a predetermined point in each segment corresponding to the number of knitted courses required to complete the head-side fashioning and thereafter lowering all needles on that

side as a unit by means of a cam, such unit being designed to provide two aggregations of blank stitches, one disposed midway therein and the other adjacent to the said predetermined point; and of continuing the widening first described on the crown end of the segment only until all needles are in active position; of raising all but ever-active needles out of action at the completion of each segment.
